STACKING AND NESTING BOXES

Lee A. Fordon, Detroit, Mich.

Application May 16, 1944, Serial No. 535,810

18 Claims. (Cl. 220—97)

This invention relates to improvements in stacking and nesting boxes.

The main objects of this invention are:

First, to provide a box well adapted for the handling of merchandise, such for example as in stores, warehouses, in delivery, and the like, which is adapted for nesting as well as for stacking.

Second, to provide a structure having these advantages in which the walls automatically swing to outwardly inclined nesting position when the stacking bars are collapsed and which are swung to and retained in erected position when the stacking bars are erected.

Third, to provide a structure which may be readily kept in a sanitary condition, bottom and wall panels of fiberboard being effectively supported and easily removed or inserted for replacement when they become soiled or broken.

Fourth, to provide a structure having these advantages which is very easily and quickly manipulated to bring the walls to erected stacking position or collapse them to nesting position.

Fifth, to provide a stacking box adapted for nesting which, while having various metal parts for the sake of durability and to facilitate keeping in a sanitary condition, is at the same time economical and durable in structure.

Objects relating to details and economies of the invention will appear from the description to follow. The invention is defined in the claims.

A preferred embodiment of the invention is illustrated in the accompanying drawings, in which:

Fig. 1 is a perspective view of a structure embodying my invention with the walls adjusted to stacking position.

Fig. 2 is a perspective view with the wall panels and bottom panels removed, with the parts in nesting position.

Fig. 3 is a perspective view similar to that of Fig. 1 with the wall panels removed thereby facilitating a better illustration of structural features.

Fig. 4 is a bottom perspective view with the bottom and wall panels in position.

Fig. 5 is an enlarged fragmentary longitudinal section with the parts in nesting position.

Fig. 6 is a fragmentary side elevational view illustrating a pair of boxes in nested condition.

Fig. 7 is an enlarged fragmentary plan view illustrating the relationship of the wall connecting straps when the parts are in nesting position.

Fig. 8 is an enlarged fragmentary plan view partially in horizontal section with the parts in erected position.

Fig. 9 is an enlarged fragmentary side elevation with the parts in erected or stacking position.

Fig. 10 is an enlarged fragmentary end elevation looking from the right of Fig. 9.

5 The embodiment of my invention illustrated comprises a bottom border frame designated generally by the numeral 1. This frame is formed of stock of angle section, the vertical flanges 2 being slit at the corners 3 so that they are springably connected to the horizontal flanges 4. The side bottom bars 5 are secured to the under sides of the flanges of the side portions or members of the bottom frame and are preferably provided with metal tips 6. The intermediate longitudinal bar 10 7 is also of wood and is secured to the under side of the horizontal flanges or end members of the bottom frame. A metal cross piece 8 extends between the side members of the bottom frame, being secured to the upper side thereof and resting on the intermediate longitudinal bar.

15 The side wall frames designated generally by the numeral 9 are formed of wire to provide top members 10, corner uprights 11, and intermediate uprights 12. These uprights are welded to the 20 vertical flanges of the bottom frame.

25 The end members designated generally by the numeral 13 are also formed of wire and conformed to provide corner uprights 14 and intermediate uprights 15 which are welded to the vertical flanges of the bottom frame.

30 The top members 10 of the side wall frames have downward offsets 16 adapted to receive the stacking bars 17, the stacking bars having camming engagement with the cammed surfaces 18 of the 35 offsets 16, see Figs. 5 and 6.

35 The stacking bars have arms 19 at the ends thereof pivoted at 20 on the corner uprights of the end members and in spaced relation to the top members of the end wall frames so that when the 40 stacking bars are swung to erected position they swing across the end uprights 11 of the side frames to swing the side walls into erected position and retain them in erected position. The arms 19 are preferably inwardly offset at 21 to provide a camming action thereby facilitating the swinging of the parts to erected position.

45 Loop-like straps 22 are pivotally mounted on the corner uprights of the end members and slidably embrace the corner uprights of the side members, acting to limit the outward spring or swing of the walls when in nesting position, as shown in Fig. 2. The straps are provided with 50 inwardly struck tongues 23, see Fig. 8, which have pivotal engagement with the corner uprights of the end wall members.

The corner uprights are preferably outwardly offset at 24 to permit the tongues to lie between the adjacent uprights, as indicated in Fig. 9, these offsets also serving as stops to prevent downward movement of the straps. However, additional stops 25 are preferably provided.

In the embodiment illustrated, when the stacking bars are collapsed at the end walls on which they are pivotally mounted, the walls automatically spring out to outwardly inclined nesting position. The adjusting of the bails to stacking position brings the walls to erected or upright position and securely locks them in that position. The ends 26 on the pivot portions 27 serve not only to retain the pivot portions within the pivot ears 20 but when the parts are in erected position they project inwardly to constitute stops for the side wall corner uprights, see for example Fig. 3. The arms 19 of the stacking bars ride along the straps 22 as the stacking bars are swung to erected position, thus facilitating the erecting manipulation. Handles 28 are provided. The side wall panels 29 are preferably integral with the bottom 30, the end wall panels 31 being preferably separate. The top pieces or bars of the side and end frames are provided with downwardly facing channels 32 adapted to receive the upper edges of the wall panels. The bottom panel 30 may be longitudinally scored to facilitate the positioning of the bottom and side panels.

After the bottom and side panels are positioned with the upper edges of the side panels within the channels 32 the end panels 31 are inserted with their lower edges resting upon the bottom panel 30 and their upper edges engaged with the downwardly facing end channels. The inner or supplemental bottom 33 is preferably provided as a reinforcement for the bottom panel 30 and also its end edges engage the lower ends of the end panels, as shown in Fig. 5. The panels may be quickly inserted or removed as occasion may require. The upper corners of the side panels are cut away at 34 while the upper corners of the end panels are cut away at 35 to provide openings for the straps 22.

It will be understood that I have used the terms "side" and "ends" as a matter of convenience in description and while boxes of this type are usually elongated, they may be square and of any suitable dimension, and opposed sides may be arbitrarily considered as ends and other opposed walls arbitrarily considered as sides.

The feature of the walls automatically springing to nesting position when the stacking bars are collapsed is a very desirable feature but satisfactory results may be had when this automatic adjustment is not present.

I have illustrated and described my invention in an embodiment which I have found highly satisfactory. I have not attempted to illustrate or describe other embodiments or adaptations as it is believed that this disclosure will enable those skilled in the art to embody or adapt my invention as may be desired.

Having thus described my invention, what I claim as new and desire to secure by Letters Patent, is:

1. In a stacking box adapted for nesting, the combination of a bottom frame of angled section disposed with the angles thereof facing inwardly and upwardly, the vertical flanges being springable, side and end wall frames comprising top members and corner uprights welded at their lower ends to the corresponding springable

flanges of said bottom frame, the top members of the side frames having outwardly cammed downward offsets therein spaced from the ends thereof and adapted to receive stacking bars, 5 loop-like straps slidably embracing the corner uprights of the side wall frames and pivotally engaging the corner uprights of the end wall frames, the corner uprights of the end wall frames having offsets adjacent the upper ends thereof constituting supporting shoulders for the straps, the straps having tongues struck inwardly therefrom to pivotally engage the corner uprights of the end wall frames, stacking bars provided with pivot arms at the ends thereof 10 pivotally mounted on the corner uprights of the end frames below the said straps, the pivot ends of said arms being downwardly offset, said arms being swingable over said straps and the adjacent corner uprights of the side frames and 15 constituting cam members facilitating swinging the wall frames to and supporting them in erected position with the stacking bars in engagement with the said camming offsets in said side frame top members, said springable vertical flanges to which said wall frames are secured being disposed to automatically spring said wall frames to an outwardly inclined nesting position when said stacking bars are swung outwardly, downwardly facing channel-shaped wall 20 panel receiving members mounted on the top members of the wall frames to receive the upper edges of wall panels arranged within the wall frames, longitudinal side and intermediate bottom bars constituting shoes, the longitudinal 25 side bottom bars being secured to the undersides of the horizontal flanges of the side members of the bottom frame, the intermediate longitudinal bottom bar being secured to the undersides of the horizontal flanges of the end members 30 of the bottom frame, a bottom cross member secured at its ends to horizontal flanges of the bottom frame side members, a combined bottom and side wall panel unit disposed with the upper edges of the side wall portions thereof in engagement within the channels of said panel receiving members, end wall panels disposed with their end edges abutting the side wall panels in erected position of said wall frames and with their upper edges engaged with 35 the channels of said panel receiving members of said end wall frames, and an auxiliary bottom member arranged within said side and end wall panels with its ends in engagement with the end wall panels for retaining them in 40 erected position.

2. In a stacking box adapted for nesting, the combination of a bottom frame of angled section disposed with the angles thereof facing inwardly and upwardly, the vertical flanges being springable, side and end wall frames comprising top members and corner uprights welded at their lower ends to the corresponding springable flanges of said bottom frame, the top members of the side frames having outwardly cammed downward offsets therein spaced from the ends thereof and adapted to receive stacking bars, 45 loop-like straps slidably embracing the corner uprights of the side wall frames and pivotally engaging the corner uprights of the end wall frames, the corner uprights of the end wall frames having offsets adjacent the upper ends thereof constituting supporting shoulders for the straps, the straps having tongues struck inwardly therefrom to pivotally engage the corner uprights of the end wall frames, stacking bars 50 provided with pivot arms at the ends thereof pivotally mounted on the corner uprights of the end frames below the said straps, the pivot ends of said arms being downwardly offset, said arms being swingable over said straps and the adjacent corner uprights of the side frames and constituting cam members facilitating swinging the wall frames to and supporting them in erected position with the stacking bars in engagement with the said camming offsets in said side frame top members, said springable vertical flanges to which said wall frames are secured being disposed to automatically spring said wall frames to an outwardly inclined nesting position when said stacking bars are swung outwardly, downwardly facing channel-shaped wall 55 panel receiving members mounted on the top members of the wall frames to receive the upper edges of wall panels arranged within the wall frames, longitudinal side and intermediate bottom bars constituting shoes, the longitudinal side bottom bars being secured to the undersides of the horizontal flanges of the side members of the bottom frame, the intermediate longitudinal bottom bar being secured to the undersides of the horizontal flanges of the end members of the bottom frame, a bottom cross member secured at its ends to horizontal flanges of the bottom frame side members, a combined bottom and side wall panel unit disposed with the upper edges of the side wall portions thereof in engagement within the channels of said panel receiving members, end wall panels disposed with their end edges abutting the side wall panels in erected position of said wall frames and with their upper edges engaged with the channels of said panel receiving members of said end wall frames, and an auxiliary bottom member arranged within said side and end wall panels with its ends in engagement with the end wall panels for retaining them in 60 erected position.

3. In a stacking box adapted for nesting, the combination of a bottom frame of angled section disposed with the angles thereof facing inwardly and upwardly, the vertical flanges being springable, side and end wall frames comprising top members and corner uprights welded at their lower ends to the corresponding springable flanges of said bottom frame, the top members of the side frames having outwardly cammed downward offsets therein spaced from the ends thereof and adapted to receive stacking bars, 65 loop-like straps slidably embracing the corner uprights of the side wall frames and pivotally engaging the corner uprights of the end wall frames, the corner uprights of the end wall frames having offsets adjacent the upper ends thereof constituting supporting shoulders for the straps, the straps having tongues struck inwardly therefrom to pivotally engage the corner uprights of the end wall frames, stacking bars 70 provided with pivot arms at the ends thereof pivotally mounted on the corner uprights of the end frames below the said straps, the pivot ends of said arms being downwardly offset, said arms being swingable over said straps and the adjacent corner uprights of the side frames and constituting cam members facilitating swinging the wall frames to and supporting them in erected position with the stacking bars in engagement with the said camming offsets in said side frame top members, said springable vertical flanges to which said wall frames are secured being disposed to automatically spring said wall frames to an outwardly inclined nesting position when said stacking bars are swung outwardly, downwardly facing channel-shaped wall 75 panel receiving members mounted on the top members of the wall frames to receive the upper edges of wall panels arranged within the wall frames, longitudinal side and intermediate bottom bars constituting shoes, the longitudinal side bottom bars being secured to the undersides of the horizontal flanges of the side members of the bottom frame, the intermediate longitudinal bottom bar being secured to the undersides of the horizontal flanges of the end members of the bottom frame, a bottom cross member secured at its ends to horizontal flanges of the bottom frame side members, a combined bottom and side wall panel unit disposed with the upper edges of the side wall portions thereof in engagement within the channels of said panel receiving members, end wall panels disposed with their end edges abutting the side wall panels in erected position of said wall frames and with their upper edges engaged with the channels of said panel receiving members of said end wall frames, and an auxiliary bottom member arranged within said side and end wall panels with its ends in engagement with the end wall panels for retaining them in erected position.

provided with pivot arms at the ends thereof pivotally mounted on the corner uprights of the end frames below the said straps, the pivot ends of said arms being downwardly offset, said arms being swingable over said straps and the adjacent corner uprights of the side frames and constituting cam members facilitating swinging the wall frames to and supporting them in erected position with the stacking bars in engagement with the said camming offsets in said side frame top members, said springable vertical flanges to which said wall frames are secured being disposed to automatically spring said wall frames to an outwardly inclined nesting position when said stacking bars are swung outwardly, and downwardly facing channel-shaped wall panel receiving members mounted on the top members of the wall frames adapted for removably receiving the upper edges of separate wall panels arranged within the wall frames.

3. In a stacking box adapted for nesting, the combination of a bottom frame of angled section disposed with the angles thereof facing inwardly and upwardly, the vertical flanges being springable, side and end wall frames comprising top members and corner uprights welded at their lower ends to the corresponding springable flanges of said bottom frame, the top members of the side frames having outwardly cammed downward offsets therein spaced from the ends thereof and adapted to receive stacking bars, loop-like straps slidably embracing the corner uprights of the side wall frames and pivotally engaging the corner uprights of the end wall frames, the corner uprights of the end wall frames having offsets adjacent the upper ends thereof constituting supporting shoulders for the straps, the straps having tongues struck inwardly therefrom to pivotally engage the corner uprights of the end wall frames, and stacking bars provided with pivot arms at the ends thereof pivotally mounted on the corner uprights of the end frames below the said straps, the pivot ends of said arms being downwardly offset, said arms being swingable over said straps and the adjacent corner uprights of the side frames and constituting cam members facilitating swinging the wall frames to and supporting them in erected position with the stacking bars in engagement with the said camming offsets in said side frame top members, said springable vertical flanges to which said wall frames are secured being disposed to automatically spring said wall frames to an outwardly inclined nesting position when said stacking bars are swung outwardly.

4. In a stacking box adapted for nesting, the combination of a bottom frame of angled section disposed with the angles thereof facing inwardly and upwardly, the vertical flanges being springable, side and end wall frames comprising top members and corner uprights welded at their lower ends to the corresponding springable flanges of said bottom frame, the top members of the side frames having outwardly cammed downward offsets therein spaced from the ends thereof and adapted to receive stacking bars, stacking bars provided with pivot arms at the ends thereof pivotally mounted on the corner uprights of the end frames and swingable over the adjacent corner uprights of the side frames and constituting cam members facilitating swinging the wall frames to and supporting them in erected position with the stacking bars in engagement with the said camming offsets

in said side frame top members, said wall frames being swingable to an outwardly inclined nesting position when said stacking bars are swung outwardly, downwardly facing channel-shaped wall panel receiving members mounted on the top members of the wall frames to receive the upper edges of wall panels arranged within the wall frames, a combined bottom and side wall panel unit disposed with the upper edges of the side wall portions thereof in engagement within the channels of said panel receiving members, end wall panels disposed with their end edges abutting the side wall panels in erected position of said wall frames and with their upper edges engaged within the channels of said panel receiving members of said end wall frames, and an auxiliary bottom member arranged within said side and end wall panels with its ends in engagement with the end wall panels for retaining them in erected position.

5. In a stacking box adapted for nesting, the combination of a bottom frame of angled section disposed with the angles thereof facing inwardly and upwardly, the vertical flanges being springable, side and end wall frames comprising top members and corner uprights welded at their lower ends to the corresponding springable flanges of said bottom frame, the top members of the side frames having outwardly cammed downward offsets therein spaced from the ends thereof and adapted to receive stacking bars, stacking bars provided with pivot arms at the ends thereof pivotally mounted on the corner uprights of the end frames and swingable over the adjacent corner uprights of the side frames and constituting cam members facilitating swinging the wall frames to and supporting them in erected position with the stacking bars in engagement with the said camming offsets in said side frame top members, said wall frames being swingable to an outwardly inclined nesting position when said stacking bars are swung outwardly, and downwardly facing channel-shaped wall panel receiving members mounted on the top members of the wall frames adapted for removably receiving the upper edges of separate wall panels arranged within the wall frames.

6. In a stacking box adapted for nesting, the combination of a bottom frame of angled section disposed with the angles thereof facing inwardly and upwardly, the vertical flanges being springable, side and end wall frames comprising top members and corner uprights welded at their lower ends to the corresponding springable flanges of said bottom frame, the top members of the side frames having outwardly cammed downward offsets therein spaced from the ends thereof and adapted to receive stacking bars, and stacking bars provided with pivot arms at the ends thereof pivotally mounted on the corner uprights of the end frames and swingable over the adjacent corner uprights of the side frames and constituting cam members facilitating swinging the wall frames to and supporting them in erected position with the stacking bars in engagement with the said camming offsets in said side frame top members, said wall frames being swingable to an outwardly inclined nesting position when said stacking bars are swung outwardly.

7. In a stacking box adapted for nesting, the combination of a bottom frame, side and end wall frames carried by said bottom frame, said bottom frame and wall frames having resilient connect-

ing means to automatically spring said wall frames to outwardly inclined positions when unrestrained, said side and end wall frames comprising top members and corner uprights, the top members having cammed offsets adjacent the ends thereof, straps pivotally engaging the corner uprights of the end walls and slidably engaging the outer sides of the corner uprights of the side walls for limiting the outward movement of the wall frames, stacking bars provided with pivot arms at the ends thereof pivotally mounted on the corner uprights of the end frames below said straps and swingable over said straps and the adjacent corner uprights of the side frames to engage said stacking bars with said offsets and acting to hold the side wall frames in erected position when the stacking bars are in operative stacking position, the wall frames automatically swinging to outwardly inclined nesting position when the stacking bars are swung outwardly, the top members of said side and end wall frames being provided with downwardly facing wall panel receiving channels, and removable side wall panels notched at the corners to receive said straps, the upper edges of the side wall panels being detachably engageable with said channels.

8. In a stacking box adapted for nesting, the combination of a bottom frame, side and end wall frames carried by said bottom frame, said bottom frame and wall frames having resilient connecting means to automatically spring said wall frames to outwardly inclined positions when unrestrained, said side and end wall frames comprising top members and corner uprights, the top members having cammed offsets adjacent the ends thereof, stacking bars provided with pivot arms at the ends thereof pivotally mounted on the corner uprights of the end frames and swingable over the adjacent corner uprights of the side frames to engage said stacking bars with said offsets and acting to hold the side wall frames in erected position when the stacking bars are in operative stacking position, the wall frames automatically swinging to outwardly inclined nesting position when the stacking bars are swung outwardly, the top members of said side and end wall frames being provided with downwardly facing wall panel receiving channels, and removable side wall panels, the upper edges of the side wall panels being detachably engageable with said channels.

9. In a stacking box adapted for nesting, the combination of a bottom frame, side and end wall frames carried by said bottom frame, said bottom frame and wall frames having resilient connecting means to automatically spring said wall frames to outwardly inclined positions when unrestrained, said side and end wall frames comprising top members and corner uprights, the top members having cammed offsets adjacent the ends thereof, straps pivotally engaging the corner uprights of the end walls and slidably engaging the outer sides of the corner uprights of the side walls for limiting the outward movement of the wall frames, and stacking bars provided with pivot arms at the ends thereof pivotally mounted on the corner uprights of the end frames below said straps and swingable over said straps and the adjacent corner uprights of the side frames to engage said stacking bars with said offsets and acting to hold the side wall frames in erected position when the stacking bars are in operative stacking position, the wall frames automatically swinging to outwardly inclined nesting position when the stacking bars are swung outwardly.

10. In a stacking box adapted for nesting, the combination of a bottom frame, side and end wall frames carried by said bottom frame, said bottom frame and wall frames having resilient connecting means to automatically spring said wall frames to outwardly inclined positions when unrestrained, said side and end wall frames comprising top members and corner uprights, the top members having cammed offsets adjacent the ends thereof, and stacking bars provided with pivot arms at the ends thereof pivotally mounted on the corner uprights of the end frames and swingable over the adjacent corner uprights of the side frames to engage said stacking bars with said offsets and acting to hold the side wall frames in erected position when the stacking bars are in operative stacking position, the wall frames automatically swinging to outwardly inclined nesting position when the stacking bars are swung outwardly.

11. In a stacking box adapted for nesting, the combination of a bottom frame, side and end walls connected to said bottom frame, said bottom frame and wall frames having resilient connecting means to automatically spring said wall frames to outwardly inclined positions when released, straps connecting the adjacent ends of the side and end walls to limit the outward swing thereof, and stacking bars pivotally mounted on the end walls to swing to the outer sides thereof and swingable over the side walls, and means including said straps connecting said walls and stacking bars whereby the swinging of the stacking bars to operative stacking position acts to swing the walls to erected position.

12. In a stacking box adapted for nesting, the combination of a bottom frame, side and end walls connected to said bottom frame, said bottom frame and wall frames having resilient connecting means to automatically spring said wall frames to outwardly inclined positions when released, and stacking bars pivotally mounted on the end walls to swing to the outer sides thereof and swingable over the side walls, and means connected to said stacking bars and to said side and end walls whereby the movement of the stacking bars to operative stacking position and the movement of the walls to erected position may be simultaneously effected.

13. In a stacking box adapted for nesting, the combination of a bottom frame, side and end walls connected to said bottom frame to swing outwardly to an inclined nesting position, straps connecting the walls to limit the outward swing thereof, and stacking bars mounted on the end walls to swing to the outer sides thereof and swingable over the side walls, and means including said straps connecting said walls and stacking bars whereby the swinging of the stacking bars to erected position acts to swing the walls to operative stacking position, and means including said bottom frame and said side and end walls for automatically swinging said walls to outwardly inclined nesting position when the stacking bars are swung outwardly.

14. In a stacking box adapted for nesting, the combination of a bottom frame, side and end walls connected to said bottom frame to swing outwardly to an inclined nesting position, and stacking bars mounted on the end walls to swing to the outer sides thereof and swingable over the side walls, and means connected to said stacking bars and to said side and end walls whereby the movement of the stacking bars to operative stacking

position and the movement of the walls to erected position may be simultaneously effected.

15. In a stacking box adapted for nesting, the combination of a bottom frame, side and end walls connected to said bottom frame to swing outwardly to an inclined nesting position, straps connecting the adjacent ends of the side and end walls, and stacking bars pivotally mounted on the end walls to swing to the outer sides thereof and swingable across said straps to facilitate the swinging of the side walls to erected position.

16. In a stacking box adapted for nesting, the combination of a bottom structure, wall structures associated with the bottom structure, said wall structures being resiliently connected to said bottom structure to automatically spring outwardly to inclined nesting position when released, connections for the adjacent ends of the side and end walls for limiting the outward swinging thereof, and stacking bars adjustably mounted on one pair of opposed wall structures for engagement with the other pair of opposed wall structures when the stacking bars are in operative stacking position, the stacking bars acting to hold the wall structures in erected position when the stacking bars are in stacking position.

17. In a stacking box adapted for nesting, the

combination of a bottom structure, wall structures associated with the bottom structure, said wall structures being connected to said bottom structure to swing outwardly to inclined nesting position, connections for the adjacent ends of the side and end walls for limiting the outward swinging thereof, and stacking bars adjustably mounted on one pair of opposed wall structures to be adjusted for engagement with the other pair of opposed wall structures when the stacking bars are in operative stacking position, the stacking bars acting to hold the wall structures in erected position when the stacking bars are in stacking position.

18. In a stacking box for nesting, the combination of a bottom structure, wall structures associated with the bottom structure, said wall structures being connected to said bottom structure to swing outwardly to inclined nesting position, and stacking bars adjustably mounted on one pair of opposed wall structures to be adjusted for engagement with the other pair of opposed wall structures when the stacking bars are in operative stacking position, the stacking bars acting to hold the wall structures in erected position when the stacking bars are in stacking position.
